UNITED STATES PATENT OFFICE.

JOHN FRANCO, OF SAN FRANCISCO, CALIFORNIA.

TRACTOR-TREAD

1,305,593.

Specification of Letters Patent. Patented June 3, 1919.

Application filed February 21, 1918. Serial No. 218,436.

To all whom it may concern:

Be it known that I, JOHN FRANCO, a citizen of Switzerland, and a resident of the city and county of San Francisco and State 5 of California, have invented a certain new and useful Tractor-Tread, of which the following is a specification.

The invention relates to endless treads or tracks for tractors of the caterpillar or track 10 laying type.

An object of the invention is to provide a tractor tread composed of a plurality of hinged links or plates having overlapping edges which lie above the ground engaging 15 surfaces of the plates.

Another object of the invention is to provide a tread formed of hinged plates in which dirt or earth cannot lodge and pack in the joints between the successive plates.

20 A further object of the invention is to provide means for preventing the hinge pin from rotating in its bearings.

The invention possesses other advantageous features, some of which, with the foregoing, will be set forth at length in the following description where I shall outline in full that form of the invention which I have selected for illustration in the drawings accompanying and forming part of the 25 present specification. In the drawings I have shown one specific form of tread plate but it is to be understood that I do not limit myself to such form, since the invention, as expressed in the claims, may be embodied 30 in a plurality of forms.

Referring to said drawings—

Figure 1 is a plan view of the under or ground engaging side of two connected tread plates.

40 Fig. 2 is a plan view of the upper side of two connected tread plates.

Fig. 3 is a side elevation of two connected plates.

Fig. 4 is a vertical section taken along 45 the center line of said plates.

The tread of my invention consists of a plurality of hinged tread plates 2, all of the plates being identical and being constructed so that they fit together to form 50 the tread. The plate is preferably rectangular in shape and is provided on its lower or ground engaging surface with a transverse rib or projection 3 arranged adjacent one end, which forms a grouser or ground gripping element. Adjacent the opposite end the plate is preferably provided with two spaced 55

flat low projections 10 which serve as seats through which holes may be formed for bolting grousers or other extension plates to the plates. On its upper side the plate is provided at one end with a centrally disposed cylindrical eye or hinge knuckle 4 and at its other end is provided with spaced complementary eyes 5, adapted to lie adjacent the ends of the eye 4 on the adjacent plate 2 60 and form therewith a hinge knuckle. The holes through the eyes 4 and 5 are of the same diameter and the hinge is completed by the bolt or hinge pin 6, extending through the eyes. The outer surfaces of the eyes 70 5 are spaced inwardly from the side edges of the plates and a boss 7 is formed on the under side of the plate between each eye 5 and the side edge of the plate. The bolt 6 is provided on its end with a square head 8 75 which engages the boss, thereby preventing the bolt from rotating in the eyes. The bolt is preferably held against longitudinal displacement by a cotter-pin 9 passing through the end thereof. 80

The eye 4 has a cylindrical exterior surface and projects beyond the transverse edge of the plate and the eyes 5 have similar cylindrical exterior surfaces and extend beyond the other transverse edge of the plate 85 and when the plates are assembled the eyes 4 and 5 overlap into axial alignment and the transverse edges are brought into contact or approximate contact. The bosses 7 project beyond the transverse edge of the plate and 90 are curved on their under surfaces to lie in the cylindrical plane of the outer surfaces of the eyes 5. In other words, the under surfaces of the bosses are concentric with the bolt 6. These bosses and eyes 5 overlie 95 the transverse edge of the adjacent plate, forming overlapping joints at the opposite sides of the plates which prevent the entrance of earth into the joint in such quantity as to interfere with its action. At the 100 center of the plate, or between the overlap at the sides, the transverse edge of the other plate underlies the eye 4 on the first plate, forming an overlap in the opposite direction. Considering two hinged plates, the 105 first plate overlaps the second at the side edges and the second overlaps the first at the central part, which is that part which lies between the edge overlapping portions. The tread plates are arranged in alinement 110 and the overlapping portions are disposed above the lower surfaces of the plates,

The eyes 4 and 5 are joined on the upper side of the plate by the ribs or tracks 13, the outer edges of which are preferably parallel to the side edges of the plate. At the 5 end where it meets the eye 4 the outer edges of the tracks are turned in to meet the ends of the eye 4 to provide spaces for the eyes 5 on the next plate, and at the other end of the plate the tracks merge into the eyes 5.

10 In fact, the eyes 5 form parts of the tracks. The tracks are of the same height as the eyes, so that a flat-surfaced track is formed longitudinally of each plate. At their ends adjacent the eye 4 the tracks are undercut 15 to lighten the plate.

I claim:

1. An endless tractor tread composed of a plurality of tread plates arranged in alinement, hinge joints connecting said plates together, extensions on one plate overlapping the hinge joint with the contiguous plate adjacent the side edges thereof, and an extension on the contiguous plate overlapping the hinge joint with the first plate between 25 the said side extensions.
2. An endless tractor tread composed of a plurality of hinge tread plates arranged in alinement, each plate having an eye on one end, and a plurality of eyes on the other 30 end, the eye on one end being alined axially with the eyes on the other end of the next contiguous plate, an extension on one plate between the eyes on one end overlapping the eye on the next contiguous plate, and in contact with the surface thereof and extensions 35 on the other end of the plate at the sides of the eye and overlapping the eyes on the next contiguous plate.
3. An endless tractor tread composed of 40 a plurality of ground engaging tread plates arranged in alinement, an eye on one end of each plate, a plurality of eyes on the other end of each plate, the eye on one plate being alined axially with the plurality of eyes on

the contiguous plate, a bolt extending 45 through said alined eyes, a head on said bolt having a flat side and a boss on the ground engaging plate extending over the edge of the next contiguous plate and engaged by said flat side to prevent the bolt 50 from turning.

4. An endless tractor tread composed of a plurality of hinged tread plates each having a centrally disposed projecting eye on one end overlying the next contiguous plate 55 and a plurality of spaced projecting eyes on the other end overlying the next contiguous plate at that end, and disposed on opposite sides of the central eye on said next contiguous plate and projections extending 60 transversely outward from said second mentioned eyes and overlying the next contiguous plate on the sides of said centrally disposed projecting eye.

5. An endless tractor tread composed of 65 a plurality of hinged tread plates each having a centrally disposed cylindrical eye on one end overlying the next contiguous plate, and a plurality of spaced cylindrical eyes on the other end overlying the next contiguous 70 plate at that end and arranged in alinement with the central eye on the next contiguous plate, a hinge pin extending through said alined eyes and projections having curved under surfaces concentric with said 75 hinge pin extending from one plate adjacent said second mentioned eyes and overlying the next contiguous plate at the sides of its surface and a central projection on the said next contiguous plate between said eyes 80 overlying the said first plate at the center of its surface.

In testimony whereof, I have hereunto set my hand at San Francisco, California, this 9th day of February, 1918.

JOHN FRANCO.

In presence of—
H. G. PROST.
